DEVICE FOR BOOMING LIFEBOATS

Charles L. Montanti, Fort Wadsworth, N. Y.

Application January 8, 1945, Serial No. 571,721

4 Claims. (Cl. 9—46)

1

This invention relates to a device for booming a lifeboat in an outboard position in conjunction with apparatus for swinging the lifeboat between an inboard and the outboard position with respect to a ship's deck.

The principal object of the invention is the provision of a device of the indicated character which enables a lifeboat to be put in an outboard position and an inboard position in less time and with less labor than heretofore.

The nature of the invention and its distinguishing features and advantages will appear when the following specification is read in connection with the accompanying drawings, in which—

Fig. 1 is a perspective view showing a lifeboat boomed off in an outboard position in accordance with the present invention.

Fig. 2 is an end view of the booming device, the boom being shown in full lines in an inboard position, and the boom also being shown in dotted lines in an outboard booming position.

Fig. 3 is a fragmentary top plan view.

Fig. 4 is a sectional view taken on the line 4—4 of Fig. 2.

Referring now to Fig. 1 it will be seen there are shown a lifeboat 19, davits 11 pivotally connected adjacent the fish plate or edge of a ship's deck 12, gear 13 supported by the davits and connected with the lifeboat for lowering and raising the lifeboat, and chocks 14 on the deck 12. The davits 11 are swingably mounted for the purpose of swinging the lifeboat between an inboard and an outboard position with respect to the deck 12. Means 15 are provided for swinging the davits for the stated purpose.

In accordance with the present invention, a boom 16 of any suitable length and cross-sectional size and shape is rigidly supported at the ends thereof on the upper ends of arms 17 between the arms. Each arm 17 consists of a T iron in the present instance, and each is cut away to provide an unflanged lower end portion. A cross-piece 18 is secured to the upper end of each arm 17 and a clip 19 engaged with the related end of the boom 16 is secured to the cross-piece 18, as at 20. A brace 21 is connected with the arms 17 between them. The lower end of each arm 17 is pivotally connected, as at 22, with a channel iron 23, or other suitable attachment, anchored to the deck 12 in any suitable manner. The channel iron 23 has a longitudinal slot 24 therein to accommodate the lower end portion of the related arm 17. The slot terminates short of both ends of the channel iron 23. A bracket 25

2

25 is welded or otherwise secured to the top of each channel iron 23 intermediate the ends thereof. The bracket 25 provides spaced plates 26 and a stop 27 between the plates. These plates are upstanding at opposite sides respectively of the slot 24.

The boom 16 has pads or cushions 28. Each pad or cushion may be of any suitable type, and in the present instance consists of a bag structure of stout fabric such as canvas, filled with sawdust, cork or equivalent material.

In order to retain the boom 16 in the active or booming position, the plates 26 of each bracket 25 have a pair or pairs of registering holes 29 therein which receive a pin 30 while extending through a hole 31 in the related arm 17.

The lifeboat is retained inboard resting on the chocks 14 and held thereon by suitable grips or other means attached to the deck and the lifeboat, together with means on the deck detachably engaged with the keel of the lifeboat. When the lifeboat is in the inboard position, the boom rests idly on the deck, as shown in Fig. 2, between the chocks 14.

When it is desired to boom the lifeboat outboard for emergency purposes, the lifeboat is freed and the davits 11 swung outward to carry the lifeboat into an outboard position beyond the fish plate or edge of the deck 12. The boom 16 then may be quickly and easily swung to a booming position in which the pads 28 contact the side of the lifeboat. The pins 30 are thrust through the plates 26 and the arms 17 by reason of the holes 29 and 31 to hold the boom in set position. Suitable lashing 32 attached to the lifeboat and the deck 12 cooperate with the boom 16 to prevent the lifeboat from moving laterally or swaying. In this manner the lifeboat is effectually boomed in the outboard position ready for an emergency, as shown in Fig. 1. The booming operation may be accomplished quickly and with a minimum of labor.

The stops 27 cooperating with the arms 17 respectively prevent them from swinging outwardly too far and make it easy to insert the pins 30.

I claim:

1. In an apparatus for booming into outboard position, a lifeboat connected at its ends by tackle 50 to the upper ends of two davit stanchions from an inboard position on chocks disposed between said stanchions and spaced inboard of said stanchions, the stanchions extending upwardly from the edge of the deck, and the upper ends thereof 55 extending outboard of the edge of the deck in

outboard position, of a pair of brackets secured to the deck of the vessel disposed between said stanchions and spaced inboard of said stanchions, but outboard of said chocks, said brackets each including an outwardly inclined shoulder, a pair of arms each pivotally connected at its lower end to one of said brackets and movable from an inwardly extending position to an outwardly inclined position where it is resting on one inclined shoulder, said brackets being also disposed closer together than said chocks, a boom connected to the outer free ends of said arms, and two pads spaced from one another and mounted on said boom to engage the side of the lifeboat when said arms are resting on said shoulders in an outward position whereby the supporting strain of the lifeboat in outboard position in part is transmitted directly to the deck, said boom, pads and arms in inboard position lying between said chocks.

2. In an apparatus for booming into outboard position, a lifeboat connected at its ends by tackle to the upper ends of two davit stanchions from an inboard position on chocks disposed between said stanchions and spaced inboard of said stanchions, the stanchions extending upwardly from the edge of the deck, and the upper ends thereof extending outboard of the edge of the deck in outboard position, of a pair of brackets secured to the deck of the vessel disposed between said stanchions and spaced inboard of said stanchions, but outboard of said chocks, said brackets each including an outwardly inclined shoulder, a pair of arms each pivotally connected at its lower end to one of said brackets and movable from an inwardly extending position to an outwardly inclined position where it is resting on one inclined shoulder, said brackets being also disposed closer together than said chocks, a boom connected to the outer free ends of said arms, two pads spaced from one another and mounted on said boom to engage the side of the lifeboat when said arms are resting on said shoulders in an outward position whereby the supporting strain of the lifeboat in outboard position in part is transmitted directly to the deck, said boom, pads and arms in inboard position lying between said chocks, and pins in said brackets for anchoring said arms in outward position.

3. In an apparatus for booming into outboard position, a lifeboat connected at its ends by tackle to the upper ends of two davit stanchions from an inboard position disposed between said stanchions and spaced inboard of said stanchions, the stanchions extending upwardly from the edge of the deck, and the upper ends thereof extending outboard of the edge of the deck in outboard position, of a pair of brackets secured to the deck of the vessel disposed between said stanchions and spaced inboard of said stanchions, said brackets each including two side plates and an outwardly inclined shoulder, a pair of arms each pivotally connected at its lower end to one of said brackets and movable from an inwardly extending position to an outwardly inclined position where it is disposed between one pair of side plates and resting

- on one inclined shoulder, a boom shorter than the lifeboat to be boomed connected to the outer free ends of said arms, and pads spaced from one another and mounted on said boom to engage the side of the lifeboat when said arms are resting on said shoulders in an outward position, said stanchions and brackets being remotely spaced from one another to facilitate independent handling of the boom and tackle without danger of interference whereby the supporting strain of the lifeboat in outboard position in part is transmitted directly to the deck, said boom, pads and arms in inboard position lying between said chocks.
- 5 4. In an apparatus for booming into outboard position, a lifeboat connected at its ends by tackle to the upper ends of two davit stanchions from an inboard position disposed between said stanchions and spaced inboard of said stanchions, the stanchions extending upwardly from the edge of the deck, and the upper ends thereof extending outboard of the edge of the deck in outboard position, of a pair of brackets secured to the deck of the vessel disposed between said stanchions and spaced inboard of said stanchions, said brackets each including two side plates and an outwardly inclined shoulder, a pair of arms each pivotally connected at its lower end to one of said brackets and movable from an inwardly extending position to an outwardly inclined position where it is disposed between one pair of side plates and resting on one inclined shoulder, a boom shorter than the lifeboat to be boomed connected to the outer free ends of said arms, and pads spaced from one another and mounted on said boom to engage the side of the lifeboat when said arms are resting on said shoulders in an outward position, and pins in said side plates for anchoring said arms in outward position, said stanchions and brackets being remotely spaced from one another to facilitate independent handling of the boom and tackle without danger of interference whereby the supporting strain of the lifeboat in outboard position in part is transmitted directly to the deck, said boom, pads and arms in inboard position lying between said chocks.
